CLAIM

I claim the ornamental design for a water bottle, as shown and described.

DESCRIPTION

FIG. 1 is a perspective view of the water bottle from the bottom, showing my design;

FIG. 2 is a perspective view thereof from the top;

FIG. 3 is a perspective view thereof from a slight downward angle, showing the channel through the bottle;

FIG. 4 is a side view thereof;

FIG. 5 is an opposite side view thereof;

FIG. 6 is a front view thereof;

FIG. 7 is a back view thereof;

FIG. 8 is a top view thereof; and,

FIG. 9 is a bottom view thereof.
